INVENTOR

BY Louis H. McKee,
Wiedersheim & Fairbanks
ATTORNEYS.

UNITED STATES PATENT OFFICE.

LOUIS H. MCKEE, OF TRENTON, NEW JERSEY.

BACK OR SEAT FOR CHAIRS, &c.

SPECIFICATION forming part of Letters Patent No. 618,181, dated January 24, 1899.

Application filed April 23, 1898. Serial No. 678,573. (No model.)

To all whom it may concern:

Be it known that I, LOUIS H. MCKEE, a citizen of the United States, residing at Trenton, in the county of Mercer, State of New Jersey, have invented a new and useful Improvement in Backs or Seats for Desks, Benches, or Similar Articles, which improvement is fully set forth in the following specification and accompanying drawings.

My invention relates to improvements in desks, benches, &c., by means of which I am enabled to greatly economize the wood or lumber employed in the manufacture of the supporting piece or plate therefor, such as the seats and backs thereof, since it has heretofore been the practice to use a thick piece of material and saw or otherwise produce upon the opposite outer surfaces thereof the desired curvatures for the seat or back.

In the present invention I take a strip of wood or similar material of rectangular or other cross-section and saw or otherwise cut the same in a sinuous manner, after which the sections are reversed and the rectilinear or outer surfaces thereof glued or otherwise secured together, thus producing at a single operation a seat or back having the desired curvature on both sides thereof, the strength of the finished article being greatly increased, since the grain of the different sections can be placed so as to run oppositely to each other.

It further consists of novel details of construction, all as will be hereinafter fully set forth, and particularly pointed out in the claims.

Figure 1 represents a perspective view of a chair or bench having a seat and back embodying my invention. Fig. 2 represents an end elevation of a piece of lumber or other material, showing the first step in carrying out my invention. Fig. 3 represents an end view of the finished product, which consists of the parts seen in Fig. 2, the same having been reversed and glued or otherwise secured in position. Figs. 4 and 5 represent, respectively, the initial and final steps in the production of a back for a desk or bench in which a plurality of double curvatures are desired.

Similar letters of reference indicate corresponding parts in the figures.

Referring to the drawings, A designates a chair or bench having the supporting piece

or plate—in this instance the seat B—applied thereto, said seat consisting of the upper and lower sections C and D, in the production of 55 which I employ a single piece of material E, having rectilinear upper and lower surfaces F and G, said material being severed in any suitable manner on a sinuous line, so as to form the double curve H of substantially the contour seen in Fig. 2. The material having been severed on the line H, as indicated, the sections are reversed and the rectilinear surfaces F and G are glued or otherwise secured together, whereupon it will be apparent that 60 the upper and lower surfaces of the finished seat B are provided with double curvatures which are parallel, the contour of the same corresponding to the line H.

In Fig. 5, J designates a piece of timber 70 which has the upper and lower rectilinear surfaces K and L, while M designates a sinuous cut intermediate said rectilinear surfaces, which latter are next reversed and placed in juxtaposition, as indicated in Fig. 5, and glued 75 or otherwise secured together, whereby the completed supporting piece or plate—in this instance the back N—is formed, the manner of producing the same being analogous to that already described with reference to Figs. 80 2 and 3.

It will be seen that by my invention a great saving of material is effected, and the seat or back is also greatly strengthened or stiffened by reversing the pieces when reassembling 85 the same, so that while the grains of the two pieces extend in the same general direction they run in opposite directions—that is to say, the continuity of the grain is disturbed by reversing the ends of the reassembled pieces. 90

Having thus described my invention, what I claim as new, and desire to secure by Letters Patent, is—

1. In a piece of furniture, an exposed supporting piece or plate, such as a seat or back, 95 consisting of sections secured together and having rectilinear meeting faces and comparatively-curved outer faces, said piece or plate having one of its curved faces exposed and forming a supporting-section of the piece 100 of furniture.

2. A supporting piece or plate for a piece of furniture, such as a seat or back therefor, composed of two sections secured together

and having rectilinear meeting faces and cor-
relatively-curved outer or wearing faces.

3. A supporting piece or plate for a piece
of furniture, such as a seat or back therefor,
5 consisting of a piece of material having rec-
tilinear faces, said piece of material being
severed on a sinuous line intermediate said
rectilinear faces, the sections thus formed be-
ing secured together with their rectilinear

faces in contact and with the ends thereof 10
reversed, and the sinuous faces forming the
outer or wearing faces of said supporting
piece or plate.

LOUIS H. MCKEE.
